UNITED STATES PATENT OFFICE.

FRED KESOT, OF MARION, INDIANA.

DESIGN FOR A LAMP CHIMNEY OR SIMILAR ARTICLE.

Application filed February 20, 1922. Serial No. 787. Term of patent 3½ years.

To all whom it may concern:

Be it known that I, FRED KESOT, a citizen of the United States, residing at Marion, in the county of Grant and State of Indiana, have invented a new, original, and ornamental Design for Lamp Chimneys or Similar Articles, of which the following is a specification, reference being had to the accompanying drawing, forming part thereof.

Fig. 1 is an elevation of a lamp chimney showing my new design.

Fig. 2 is a plan view of a portion of the lamp chimney.

I claim:

The ornamental design for a lamp chimney or similar article, as shown.

FRED KESOT.
